UNITED STATES PATENT OFFICE.

HOWARD VEIT, OF NEW YORK, N. Y.

DESIGN FOR A TEXTILE FABRIC.

Application filed April 23, 1924. Serial No. 9,361. Term of patent 3½ years.

To all whom it may concern:

Be it known that I, HOWARD VEIT, a citizen of the United States, and a resident of the city, county, and State of New York, have invented a certain new, original, and ornamental Design for Textile Fabric, of which the following is a specification, reference being had to the accompanying drawing, forming part thereof.

In the drawing the figure is a plan view of a textile fabric, showing my new design.

I claim:

The ornamental design for textile fabric, as shown.

HOWARD VEIT.
